UNITED STATES PATENT OFFICE.

WILLIAM SLEICHER, JR., OF TROY, NEW YORK.

FURNACE-COVER.

SPECIFICATION forming part of Letters Patent No. 403,152, dated May 14, 1889.

Application filed November 6, 1888. Serial No. 290,087. (No model.)

To all whom it may concern:

Be it known that I, WILLIAM SLEICHER, Jr., a resident of Troy, in the county of Rensselaer and State of New York, have invented certain new and useful Improvements in Furnace-Covers; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in furnace-covers of the arch class; and it consists of the novel construction and combination of parts hereinafter described, and pointed out in the claims.

Figure 1 of the drawings is a bottom plan view of an arched iron beam adapted to support a row of bricks. Fig. 2 is a side elevation of the beam supporting a row of bricks. Fig. 3 is a top plan view of the parts shown in Fig. 2. Fig. 4 represents by the solid lines a cross-section of the beam, taken on the broken line $x\ x$ in Fig. 1, the dotted lines representing a brick and its auxiliary supporting-link. Figs. 5, 6, 7, and 12 represent in side elevation, detached fire-bricks, showing modified forms of channels for auxiliary supporting-links and key. Figs. 8, 9, and 10 represent, in side elevation, modified forms of auxiliary brick-supporting links and key, the relative positions of the bricks and beam being indicated by dotted lines in Fig. 9. Fig. 11 is a cross-section of the iron beam similar to that shown in Fig. 4, taken at the broken line $x\ x$ in Fig. 3. Fig. 13 is a top plan view of the brick shown in Fig. 12.

Bridge-covers for furnaces are composed of a series of iron girder-beams laid side by side, each beam being arched and supporting an arched row of fire-bricks.

As heretofore constructed the beams have been made up of two arched metallic beam-plates set on edge and secured to each other by braces and cross-pieces, with an air-space between, the upper edges of the bricks resting against the lower arched edges of the

plates and held in place by end clamps only, pivoted to the ends of the plates and connected by an adjusting-rod extending the length of the beam. The effect of the intense heat to 55 which furnace-covers are subjected was sufficient to warp and twist such beam-plates and to expand the adjusting-rod connecting the end clamps to such an extent as to soon destroy the sustaining-power of the arched beam 60 and permit the bricks to fall into the furnace, destroying or greatly impairing the roof.

I form my supporting-beam of a single longitudinally and cross-sectionally or laterally arched beam of iron, thereby minimizing the 65 effect of heat to weaken the supporting-power of the beam by reason of warping and twisting the same. It is well known that the heat is less intense at the ends of the beams, which are supported by side walls of the furnace, 70 and I provide a cross-bar or lug near each end of the beam, to which one end of the adjusting-rods, passing through the end clamps, is secured, thereby lessening the length of rod and effect of the heat in expanding the same 75 to loosen the brick arch. It is well known that a row of bricks thus supported at its ends only in the form of an arch will when repeatedly subjected to intense heat be twisted and warped from its original position, 80 and that frequently the change is sufficient to break the arch and cause the bricks to fall from their support. I provide an auxiliary support for the brick arch by securing individual bricks in the arch, located intermediate of its ends, to its supporting-beam, which 85 prevents the brick arch from twisting or dropping away from its supporting-beam.

I have shown and described several kinds of auxiliary supporting mechanism for suspending individual bricks in the arch from the beam, which I term "links;" but I do not wish to be limited to any particular form of link or manner of securing the same to either the bricks or beam.

A represents the arch-beam, the longitudinal arch being shown in Fig. 2 and the cross or lateral arch in Fig. 4. The beam is provided with a vertically-projecting strengthening rib or flange, A' , and with the laterally-projecting flanges A^2 , the lower longitudinal-arched surfaces of which afford a bear-

ing for the upper edges of the bricks B, extending in a row from one end of the beam to the other, as shown in Figs. 2 and 3. That portion of the beam forming the cross or lateral arch A³ is provided with numerous openings A⁴, leading outward from the air-space inclosed by the cross-arch and the bricks, thereby facilitating the radiation of heat from the beam. Each end of the beam is also provided with a clamp, A⁵, pivoted to the upper edge of the beam, as at A⁶. The clamps are each connected with a cross-bar, A⁷, by a threaded bolt, A⁸, passing through the bar and clamp, and provided with a head on one side and an adjusting-nut, A⁹, on the other end.

While the beam is bottom side up, as shown in Fig. 1, the bricks can be laid thereon in the position shown by Figs. 2 and 3, and the clamps drawn tightly against the end bricks by means of the bolts and nuts, after which the position of the beam can be reversed, as shown in Fig. 2, and the bricks, being slightly beveled, will be retained in the arched form by the clamps.

I have shown several forms of auxiliary supporting-links having heads adapted to enter and fit apertures formed by grooves or channels cast in the contiguous sides of the bricks, and so located thereon as to register in pairs when the bricks are formed into an arch, each pair forming a link-receiving aperture.

The link B⁴, Fig. 10, is provided on one end with a hook or head, B⁵, adapted to fit the channel B⁶ in the brick B, Fig. 5, and be inserted one half in such channel and the other half in the supplementary channel in the contiguous brick, which channel is precisely the same as that shown in Fig. 5, and is not separately shown. The other end of the link is provided with an eye, B⁷, adapted to receive the wire of a staple, B⁸.

There may be any desired number of staples resting within the cross-arch of the beam and secured thereto in any known manner. I have shown by dotted lines in Fig. 4 one of the prongs of a staple embedded in the iron beam, where it could be inserted when the beam was cast. When the yokes of the staples are made of considerable length, as shown, two or more links may be secured to the same staple and slid along to properly adjust their position to the position of the bricks, so that they may project up through a vertical aperture between two bricks formed by grooves B⁹, Fig. 5, so arranged as to register with each other. The grooves B⁹ lead from the grooves B⁸ to the upper surfaces of the respective bricks. The relative positions of brick, link and staple, and beam are fully shown, partly by dotted lines, in Fig. 4.

The link may be in the form of a chain-link, the upper end being secured to a staple in the beam, as last above described.

I have shown such a link at B¹⁴ in Fig. 11. The upper end is adapted to receive the wire

of the staple B⁶, as shown, and the lower end fits the curved channel B¹⁵ in the brick, Fig. 12.

The bricks may each have an aperture 70 adapted to receive a rod, C, which may extend the whole length of the arch, as indicated by dotted lines C' in Fig. 2. With the aid of such a rod passing through the bricks longitudinally of the arch, one or two links 75 connecting the central parts of the rod and beam would positively secure all the bricks to the beam.

Whether the bricks were perforated to receive the rod C or not, it would be necessary 80 that those contiguous to the link B¹⁴ should be provided with the channel B¹⁵ to allow the bricks to fully engage with each other in forming the arch. I have indicated by dotted line C' in Fig. 12 the position of the aperture 85 adapted to receive the rod.

The links can be secured to the lateral flanges of the beam when desired, thus dispensing with staples B⁶. I have shown a link, B⁹, so adapted in Fig. 9. This link is provided with a central joint, B¹⁰, and the ends are bent upward and provided with the hooks B¹¹, adapted to be hooked onto the lateral flanges of the beam, as fully shown, partly by dotted lines, in Fig. 9. The channels B¹³, Fig. 95 7, in the bricks are made of a form adapted to receive the links after they have been hooked onto the beam. When desired, the links can be riveted at the end upon the lateral flanges of the beam, one upon each side, and their 100 laterally-projecting heads adapted to engage with the ends of the brick, beveled on its upper edges, so as to clamp the brick between them and suspend it directly from the beam. I have shown such a form of link at B¹⁶, Fig. 105 11, the upper end being secured to the lateral flange of the beam, one on each side, by the rivets C³, and the lower end having the head or hook, B¹⁷, adapted to enter the cross-channel B¹⁸ in the brick. The cross-channels 110 extend across the ends of the bricks, and have one of the channel walls nearly vertical, but slightly inclined inward, thereby giving the upper portion of the brick a dovetail appearance and effect, as shown in Figs. 11 and 12. 115 The links are first riveted to the beam, as shown in Fig. 11, and the bricks slid into the position shown in Fig. 11, being moved longitudinally of the beam.

It is apparent that all the bricks may be 120 thus secured directly to the beam by either of the kinds of links which I have described; but it is not necessary that all the link-heads should be connected with the beam.

Instead of the link-heads similar cylindrical or conical rods may be used and inserted in apertures formed by channels in the bricks, arranged to register with each other, as previously described. I have shown a conical or tapered rod, B², in Fig. 8, and in Fig. 6 a channel, B', formed in one side of the brick. The opposite side of the brick has a similar channel. When two bricks having such channels engage with each other in the

arch, they form an aperture, B', Fig. 2, adapted to receive the rod or key B², as seen in Fig. 2. It is manifest that when keys are thus inserted between the bricks one brick cannot 5 slide past another brick to fall from the arch unless the arch spreads more than half the diameter of the rod or key, and if a pair of bricks at the central part of the arch or at 10 intervals along the arch is linked to the beam, as previously described, and the intermediate 15 bricks keyed in by the rods B², as just described, it will be impossible for the arch to break or for any of the bricks to fall therefrom. A row of bricks can be thus suspended 20 from a straight beam, dispensing entirely with the arch feature, though I prefer to slightly arch the beam.

When desired, the brick-channels may be extended the whole length of the bricks, 25 adapting them to receive either keys or links. I have shown by dotted lines in Fig. 5 the channel B⁸ thus extended. It is apparent that all the bricks may be thus secured to the beam by suitable links inserted in channels in the contiguous sides of the bricks, or 30 as many of the bricks as desired or deemed necessary.

It should be observed that the auxiliary brick-supporting links which I have shown 35 and described are almost wholly inclosed by the bricks and only project therefrom at their upper sides, thus deriving perfect protection from the direct action of the furnace-heat. Links thus inclosed by the bricks will last 40 and support the bricks until the bricks themselves are burned away to such an extent as to be worthless as a protection for the iron links. The flange A' is provided with the apertures A¹⁰, adapted to receive a chain-hook in lifting the cover from the furnace-walls.

By securing, as I have shown and described, the individual members of the arch to the sustaining-beam the span of furnace-covers 45 can be increased, thereby enlarging the ca-

pacity of the furnace, and the degree of curvature in an arch of a given span can be safely reduced, thereby forcing the current of flame and heated gases within the furnace down nearer the furnace contents which are being 50 treated.

What I claim as new, and desire to secure by Letters Patent, is—

1. In a furnace-cover, a longitudinally and laterally arched brick-supporting beam made 55 of a single bar of iron, substantially as described.

2. In a furnace-cover, the combination, with a brick-supporting beam, of end clamps pivoted upon the beam, one at each end, a row 60 of fire-bricks inclosed between the clamps, and adjustable connections for securing the oscillatory ends of the clamps upon the ends of the beam, as screw-bolts A⁸ and cross-bars A⁷, substantially as described. 65

3. In a furnace-cover, the combination, with a brick-supporting beam having end clamp, of a row of clamp-inclosed bricks and a brick-supporting link connecting an individual brick in the row with the beam, substantially as described. 70

4. In a furnace-cover, the combination, with a brick-supporting beam having an end clamp, of a row of clamp-inclosed bricks having link-channels between contiguous bricks, and 75 supporting-links adapted to fit such channels secured to the iron beam, substantially as described.

5. In a furnace-cover, the combination, with a brick-supporting beam, of a row of bricks 80 having key-channels, a brick-supporting link connecting a brick central of the row with the beam, and brick-supporting keys, substantially as described.

In testimony whereof I have hereunto set 85 my hand this 2d day of November, 1888.
